Primary Examiner — Sandra S Snapp*Assistant Examiner* — Ieisha N Price(74) *Attorney, Agent, or Firm* — Hamre, Schumann,
Mueller & Larson, P.C.(57) **CLAIM**

The ornamental design for a post-tension concrete splicing device, as shown and described.

DESCRIPTION

FIG. 1 is a perspective view of a post-tension concrete splicing device;

FIG. 2 is a front elevational view thereof;

FIG. 3 is a rear elevational view thereof;

FIG. 4 is a top elevational view thereof;

FIG. 5 is a bottom elevational view thereof;

FIG. 6 is a left side view thereof, and a right side view is a mirror image of the left side view;

FIG. 7 is a section view along 7-7 in FIG. 6; and,

FIG. 8 is a section view along 8-8 in FIG. 2.

The broken lines defining threaded bolt holes illustrate environmental subject matter only and form no part of the claimed design. Surface shading lines form no part of the claimed design.

1 Claim, 5 Drawing Sheets---
